Primary Examiner — Robert M Spear*Assistant Examiner* — Kendra L Hamilton(74) *Attorney, Agent, or Firm* — Abel Law Group, LLP(57) **CLAIM**

The ornamental design for a teething device, as shown and described.

DESCRIPTION

FIG. 1 is a top front perspective view of a teething device incorporating my ornamental design;

FIG. 2 is a bottom rear perspective view of the teething device of FIG. 1;

FIG. 3 is a rear view of the teething device of FIG. 1;

FIG. 4 is a front view of the teething device of FIG. 1;

FIG. 5 is a right side view of the teething device of FIG. 1;

FIG. 6 is a left side view of the teething device of FIG. 1;

FIG. 7 is a top plan view of the teething device of FIG. 1; and,

FIG. 8 is a bottom plan view of the teething device of FIG. 1. The broken line showing of elements is included for the purpose of illustrating environmental structure and forms no part of the claimed design.
